(57) **CLAIM**

The ornamental design for an adhesive gel pad, as shown and described.

DESCRIPTION

FIG. 1 is a top perspective view of an adhesive gel pad showing my new design;

FIG. 2: is a top elevational view thereof, the rear elevational view being a mirror image thereof;

FIG. 3: is a front view thereof;

FIG. 4: is a rear view thereof; and,

FIG. 5: is a side view thereof, taken from the left side of FIG. 2, the right side view being a mirror image thereof.

1 Claim, 2 Drawing Sheets

FIG. 1
